UNITED STATES PATENT OFFICE.

WALTER I. GIBSON, OF NEW ORLEANS, LOUISIANA, ASSIGNOR OF ONE-THIRD TO
EDWARD R. GREENLAW AND ONE-THIRD TO FREDERICK M. MILLS, BOTH OF
NEW ORLEANS, LOUISIANA.

SECTIONAL RADIATOR.

1,347,219.

Specification of Letters Patent. Patented July 20, 1920.

Application filed June 13, 1917. Serial No. 174,534.

To all whom it may concern:

Be it known that I, WALTER I. GIBSON, a citizen of the United States, residing at New Orleans, in the parish of Orleans and 5 State of Louisiana, have invented certain new and useful Improvements in Sectional Radiators, of which the following is a specification.

The present invention relates to improvements in radiators and more especially to 10 those of the type adapted for use upon automobiles for cooling the circulating water for the engine. The primary objects of the invention are to provide a radiator which is 15 so constructed in units that any damaged or defective part of the radiator may be easily and quickly removed and replaced without requiring dismantling of the radiator; to provide a radiator of this class 20 wherein the water cooling units are yieldingly connected to a rigid outer member whereby the vibrations and strains to which such radiators are subjected in service will not cause injury to or leakage of these units; 25 and to provide a radiator composed of units or sections of standard size whereby replacement of any unit or section may be accomplished easily by unskilled persons and radiators of different sizes and capacities may 30 be made by assembling different numbers of units or sections.

To these and other ends, the invention consists in certain improvements, and combinations and arrangements of parts, all as 35 will be hereinafter more fully described, the novel features being pointed out particularly in the claims at the end of the specification.

In the accompanying drawings:

40 Figure 1 is a front elevation, partly in section, of an automobile radiator constructed in accordance with the present invention.

Fig. 2 represents a detail vertical section taken longitudinally of one of the radiator 45 units or sections.

Fig. 3 represents a section on the line 3—3 of Fig. 2, and

Fig. 4 is a detail sectional view of one of the nipples forming part of the means for 50 connecting each unit or section to the body of the radiator.

Similar parts are designated by the same reference characters in the several views.

The present invention is applicable gen-

erally to radiators of the type adapted for 55 use upon automobiles, and the preferred embodiment of the invention is shown in the accompanying drawings and will be hereinafter described in detail. It is to be understood that the invention is not restricted 60 to the precise construction shown as equivalent constructions are contemplated and will be included within the scope of the claims.

In the present instance, the radiator is composed of a relatively rigid outer member 65 and a suitable number of cooling units or sections which are removably and flexibly mounted within the rigid outer member. In the present instance, the rigid outer member comprises an upper water reservoir 1 70 which may be provided with the usual connection to receive the heated water from the cooling jacket of the engine, a lower reservoir 2 which may be provided with the usual outlet connection from the radiator to 75 the engine water jacket, and a pair of side members 3. The upper and lower reservoirs are of rigid construction. For example, they may be cast of metal such as cast iron or the like, and the connecting side members 80 3 extend between and rigidly space the upper and lower reservoirs. As shown, screws 4 and 5 may extend through the outer ends of the upper and lower reservoirs respectively and into the upper and lower ends 85 of the side members 3 and serve to detachably unite these parts. The bottom wall 6 of the upper reservoir is provided with holes 7, the number of which depends upon the number of cooling units or sections to be 90 used, and these holes are internally threaded. The upper wall 8 of the lower reservoir is provided with a similar number of holes 9, but these holes are unthreaded.

The cooling units or sections are arranged 95 vertically and placed between the lower wall 6 of the upper reservoir and the upper wall 8 of the lower reservoir. These units are preferably of duplicate construction and of a size which may be adopted as a standard. 100 Each unit comprises upper and lower heads 10 and 11, a suitable number of water tubes 12 extending between the heads and having their ends fitted into the respective heads, and side plates 13 and 14 may be connected 105 to and extended between the heads 10 and 11 to provide means for rigidly connecting and spacing them. Caps 15 and 16 are fitted

er the heads 10 and 11, thus providing water chambers at the upper and lower ends of the tubes whereby water may enter the upper ends of the tubes and after flowing therethrough may discharge from the lower ends thereof. The cap 15 is provided with a nipple 17 which is preferably tapered externally and projects upwardly therefrom, and the cap 16 is provided with a nipple 18 which is preferably tapered externally and projects downwardly therefrom. Fins 19 are provided whereby heat from the water flowing through the tubes may be absorbed readily by air passing the tubes as is usual in radiators of this class. A nipple 20 is provided for each section or unit, the nipple being threaded externally to fit into one of the threaded holes 7 in the lower wall 6 of the upper reservoir 1, and each nipple has a flange 21 on its lower end. A lock nut 22 is also provided for each nipple 20, it being threaded thereon.

In assembling a radiator of the construction just described, each section or unit is placed in position by inserting the nipple 18 on its lower end into the appropriate hole 9 in the upper wall 8 of the lower reservoir, a washer or gasket 23 of rubber, leather or other yielding material being first placed upon the nipple 18 whereby this washer or gasket will occupy a position between the lower wall of the cap 16 and the upper side of the wall 8 of the lower reservoir. The nipple 20 is then screwed upwardly into the wall 6 of the upper reservoir to its full extent; and after the nipple 17 on the upper end of the unit is brought into line with the nipple 20 and a washer or gasket 24 of rubber, leather or other yielding material has been placed in position around the nipple 17, the nipple 20 is turned in a direction to lower it, thereby bringing its flange 21 down upon the washer or gasket 24. The pressure exerted upon the upper end of the unit by the nipple 20 is sufficient to compress the washers or gaskets 23 and 24 to an extent sufficient to insure water-tight joints at these points. Furthermore, in order to prevent leakage of water along the thread of the nipple 20, a washer or gasket 25 of rubber, leather or other suitable material may be placed between the lower side of the wall 6 of the upper reservoir and the lock nut 22, and by tightening the lock nut 22, the washer or gasket 25 is compressed sufficiently to produce a water-tight joint at this point, and unscrewing of the nipple 20 by vibration is prevented.

The cooling portion of the radiator is composed of an appropriate number of units or sections, each of duplicate construction, and these sections or units are flexibly connected to the rigid outer member. In consequence, vibrations or strains to which the

outer member is subjected will not affect the inner cooling sections, as the shocks are absorbed by the yieldable joints, and development of leaks is avoided. Each of these units or sections may be inserted and removed without in any way disturbing the adjacent section or sections or the general structure of the radiator. Should a section or unit be injured or develop a leak, such section can be easily and quickly removed and another section or unit substituted, or if another is not available, the defective or injured section or unit may be removed and the holes 7 and 9 may be closed by corks or other suitable plugs.

Preferably, a face plate 26 is provided to cover the fittings which connect the upper ends of the units or sections to the upper reservoir. If such plate is used, it will be removably secured in place in order to afford access to the fittings when it is necessary to remove a unit for repair or replacement. Lugs 27 may be provided on the ends of the lower reservoir to attach the radiator to the frame of the automobile.

A radiator embodying the present invention enables repairs to be made on the road or elsewhere without the necessity of removing the radiator from the machine, it being necessary only to remove the defective section and replace it by a new one which can be kept on hand, or the defective section can be removed and the holes therefor plugged with corks or the like. Furthermore, by using units or sections of standard size, radiators of different sizes or capacities may be built and the units or sections thereof will be interchangeable with the units or sections of other radiators.

I claim as my invention:—

1. In a radiator, the combination of upper and lower rigid reservoirs, the bottom wall of the upper reservoir having threaded openings therein and the top wall of the remaining reservoir having similar openings without threads, a set of vertical cooling sections each having nipples at their upper and lower ends with exterior surfaces tapering to the free ends of the nipples, the lower nipples loosely and detachably engaging the openings of the lower reservoirs, cylindrical nipples secured in the screw-threaded openings of the upper reservoir and into which the nipples at the upper ends of the sections extend, each of the sections being movable longitudinally between said reservoirs and independently removable relatively to the other sections, and yielding gaskets interposed between the nipples to provide tight joints.

2. In a radiator, the combination of upper and lower reservoirs, the lower wall of the upper reservoir and the upper wall of the lower reservoir having corresponding openings therein, a plurality of cooling sections

adapted to occupy the space between the reservoirs, each section having exteriorly tapered nipples projecting from the center of its upper and lower ends, the nipples on 5 the lower end of the section frictionally and removably fitting in the respective opening in the lower reservoir, and a cylindrical nipple for each section adjustably threaded in the corresponding opening in the upper 10 reservoir and telescopically fitted over and receiving the exteriorly tapered nipple on the upper end of the section adjacent thereto, said cylindrical nipple being operative to produce and maintain compression between the upper and lower ends of the section and 15 the respective reservoirs.

In testimony whereof I have hereunto set my hand in presence of two subscribing witnesses.

WALTER I. GIBSON.
